DESIGN FOR A TABLECLOTH

Jacob F. Durrsé, New York, N. Y.

Application February 5, 1938, Serial No. 74,893

Term of patent 3½ years

To all whom it may concern:

Be it known that I, Jacob F. Durrsé, a citizen of the United States of America, residing in city of New York, county of New York, and State of New York have invented a new, original, and ornamental Design for a Tablecloth, of which the following is a specification, reference being had to the accompanying drawing, forming part thereof.

A quarter section of the cloth is indicated by dot and dash lines, the other three quarter sections being identical, but arranged in proper relation to complete the cloth.

I claim:

The ornamental design for a tablecloth substantially as shown and described.

JACOB F. DURRSE.
